RADIO TUNING APPARATUS

Sarkes Tarzian, Bryn Mawr, Pa., assignor to
Atwater Kent Manufacturing Company, Phila-
delphia, Pa.

Application February 28, 1934, Serial No. 713,267

7 Claims. (CL 250—40)

My invention relates to radio tuning apparatus employing a plurality of tunable frequency ranges. The overlapping of tuning ranges may cause undesirable reactions of one range on the next adjacent range. In the prior art attempts have been made to avoid such reactions by open circuiting sections of inductances, by short circuiting inductances, by loosening of couplings, and by shielding. This invention overcomes the difficulties of such reactions by a novel arrangement of circuits and parts as may be best understood by reference to the accompanying figures and specification.

Figure 1 is a simplified circuit diagram of a multi-range tunable radio frequency amplifier and detector employing my invention.

Figure 2 illustrates a preferred form of arrangement of my invention.

Referring to Figure 1, the antenna is connected to switch blade 1 which may be set on switch contact 2, 2', 2'', or 2'''. Each of these contacts successively connect to antenna inductance coils 3, 3', 3'', and 3'''. The antenna inductance coils are each grounded. Each of the coils has coupled to it a secondary inductance coil; i. e., 3 is coupled to 4, 3' to 4', 3'' to 4'', and 3''' to 4'''. The secondary inductance coils each have connected in parallel individual trimmer capacities 5, 5', 5'', and 5'''. The secondary inductances are grounded at one terminal; the other connects to switch points 6, 6', 6'', and 6'''. Switch arm 7 connects to contact points 6, etc. and to the grid of radio frequency vacuum tube 8. The switch blade is also connected to the stator plates of the main variable tuning condenser C1. The rotor plates are grounded. The cathode of tube 8 is grounded through resistor 9 which is bypassed by fixed condenser 10.

The plate of tube 8 connects to switch blade 11 which contacts points 12, 12', 12'', or 12'''. These switch points are connected to the primary inductances 13, 13', 13'', and 13'''. The remaining terminal of the inductances connects to +B of the plate battery which is illustrated at 14 and bypassed by fixed condenser 15. Each of primaries 13 to 13''' is coupled respectively to secondary inductances 16, 16', 16'', and 16'''. The secondary inductances are grounded at one terminal and are shunted by individual trimmer capacities 17, 17', 17'', and 17'''. The high potential terminal of each secondary inductance connects respectively to switch points 18, 18', 18'', and 18'''. Switch arm 19 contacts switch points 18 etc. and is also connected to main tuning condenser C2 and grid condenser 20. The grid condenser connects switch arm 19 and the grid of the vacuum tube detector 21. The grid is grounded through grid leak 22. The cathode of tube 21 is grounded. The plate of this tube connects to telephone receivers 23 which are bypassed by

fixed condenser 24. The telephone receiver circuit is completed through B-battery 14, which has its negative terminal grounded. In place of telephone receivers a vacuum tube amplifier may be employed.

For the sake of simplicity the battery to heat the filament circuits of tubes 8 and 21 is omitted. Description of the filament circuit is unnecessary, being well known to those skilled in the art.

The enclosed dotted lines of Figure 1 represent shields which house the radio frequency transformer systems. Each shield is grounded. S1 houses 3, 4, 5, and 3', 4', 5'. S2 houses 3'', 4'', 5'', and 3''', 4''', 5'''. S3 houses 13, 16, 17, and 13', 16', 17'. S4 houses 13'', 16'', 17'', and 13''', 15 16''', 17'''.

The operation of the system with the switch arms 1, 11, and 19 on the uppermost contacts is the well known, conventional tunable radio frequency amplifier and detector. Each successive position of the switch arms, which for convenience may be linked together by insulated coupling arrangements 25, results in a different tunable frequency range. By way of example:

Switch contact	Tunable range	Inductances
2, 6, 12, 18	Kilocycles	Microhenries
2'', 6'', 12'', 18''	540 to 1600	220
2', 6', 12', 18'	1600 to 4000	25
2'', 6'', 12'', 18'''	4000 to 10500	5
2'', 6'', 12'', 18'''	10500 to 20000	1

Unless precautions are taken the natural frequency of a lower frequency range will lie within the next adjacent range causing undesirable reaction. This resulting reaction may best be expressed by the equation

$$f' = \frac{f}{\sqrt{1 \pm K}}$$

when f' =resulting frequency, f =frequency before coupling, and K =coefficient of coupling. If two ranges overlap and the coupling between the circuits is close, each will react on the other. For example, at 10% coupling, if each circuit happens to be tuned to the same frequency, the desired frequency will be altered by $\pm 10\%$. At 20% coupling the reaction causes deflections of $\pm 20\%$ from the desired frequency. Even if the circuits do not happen to be tuned to the same frequency, reaction will result.

The amount of such reaction may be determined from the equation:

$$f' = \sqrt{\frac{f_1^2 + f_2^2 \pm \sqrt{(f_1^2 + f_2^2)^2 - 4f_1^2 f_2^2 (1 - K^2)}}{2(1 - K^2)}}$$

where f' =resulting frequency, f_1 =frequency of one tuned circuit, f_2 =frequency of other tuned circuit, K =coefficient of coupling. An examina-

tion of the equation will show that the further apart the frequency of the two circuits and the less the coupling, the less each will react on the other.

5 I propose to minimize this reaction by the ar-
rangement shown in Figures 1 and 2. S_1 and S_2
represent shielded grounded containers of copper
or other suitable metal. P_1 and P_2 represent in-
sulated coil forms, 4 represents the secondary in-
10 ductance of lattice winding type of the range
540 to 1600 kilocycles. 4' is the inductance of
range 4000 to 10,500 kilocycles. 4'' is the induct-
ance of range 1600 to 4000 kilocycles, and 4''' the
inductance of range 10,500 to 20,000 kilocycles.
15 With this arrangement the natural frequency
of inductance 4 and capacity 5 (including stray
capacities) is sufficiently removed from the low
frequency limit of 4', 5', and C_1 , so that in spite
of the coupling between 4 and 4', which is the
20 result of relatively close windings on the common
form P_1 , undesirable reaction is substantially
eliminated. In a similar manner 4'' and capacity
5'' (including stray capacities) will not have a
natural frequency which will be near the low fre-
25 quency range of 4''', 5''', and C_1 . Since the cir-
cuits within S_1 are shielded from the circuits
within S_2 , there can be no mutual reactions be-
tween these circuits. It should be understood
29 that a single shield S_1 may be used to prevent re-
actions from circuits having adjacent or over-
lapping frequency ranges.

Thus it becomes possible to avoid undesirable reactions between tuned circuits of used and unused ranges without attempting extreme looseness of coupling which requires spacing beyond the limits of a compact receiver, or pluralities of separate shields and coil forms. By this novel arrangement of circuits and frequency ranges, I have found that two coil forms and one shield may replace four coil forms and four shields with great resulting savings of expense and space.

The same treatment of the tuned circuits of the detector will be used with the same resulting saving and efficiency of operation. It will be understood that the variable condensers C_1 and C_2 may be ganged together and that the individual trimmers on each tuned circuit are adjusted to permit single dial operation and also to prevent undesirable reactions from overlapping tuning ranges. In the event that a superheterodyne circuit is used, my invention may be employed in the various tunable circuits, including the oscillator circuits.

I claim:

55 1. In a multi-range radio frequency tuning system, the combination of a plurality of circuits, comprising inductances and capacities, said inductances being of substantially different values, said capacities permanently connected in parallel
60 to said inductances, the maximum frequency of each of said circuits being substantially different, means for providing mutual coupling between two circuits of said plurality used in non-overlapping frequency ranges means for substantially eliminating coupling between circuits used in overlapping frequency ranges, a variable capacity, and
65 means for successively connecting said variable capacity to each of said circuits.

70 2. In a multi-range radio frequency tuning system, the combination of a plurality of circuits, comprising inductances and capacities, said inductances being of substantially different values.

5
10
said capacities permanently connected in parallel to said inductances, the maximum frequency of each of said circuits being substantially different, means for providing mutual coupling between two circuits of said plurality used in non-overlapping frequency ranges, a variable capacity, means for successively connecting said variable capacity to each of said circuits and means for minimizing coupling between circuits of said plurality used in overlapping frequency ranges, whereby undesirable reactions are avoided.

3. In a multi-range radio frequency tuning system, the combination of a plurality of inductances of different values, means for providing mutual coupling between said inductances used in non-adjacent frequency ranges, means insuring substantially zero coupling between said inductances used in adjacent frequency ranges, and a variable capacity connected to one of said inductances for tuning over a range of frequencies, whereby undesirable reactions are avoided. 15 20

4. In a multi-range radio frequency tuning system, the combination of a plurality of inductances of different values, trimmer capacities connected in parallel to each of said inductances, means insuring substantially zero coupling between pairs of said inductances and capacities used in adjacent frequency ranges, means for providing mutual coupling between pairs of said inductances and capacities used in non-adjacent frequency ranges, a variable capacity, and means for connecting said variable capacity to any one of said inductances, whereby said inductance may be made resonant at any frequency within a range of frequencies without undesirable reactions resulting from said mutual coupling. 25 30 35

5. In a multi-range radio frequency tuning system, the combination of inductances of substantially different values supported on a common form, means for providing mutual coupling between said inductances, separate adjustable capacities permanently connected in parallel to said inductances, the circuits comprising said inductances and capacities being used in non-adjacent ranges, another circuit of inductance and capacity for use in frequency ranges adjacent to the frequency ranges employing the first mentioned circuits, means insuring substantially zero coupling between circuits of adjacent ranges, and means for successively connecting a variable capacity to each of said circuits for tuning through a range of frequencies. 40 45 50

6. In a multi-range radio frequency tuning system, the combination of a plurality of inductances, means substantially eliminating coupling between said inductances used in adjacent frequency ranges, means for providing mutual coupling between said inductances used in non-adjacent frequency ranges, and a variable capacity selectively connected to one of said inductances for tuning through a range of frequencies. 55 60

7. In a multi-range radio frequency tuning system, the combination of a plurality of inductances, trimmer capacities connected in shunt to said inductances, means substantially eliminating coupling between said inductances used in adjacent frequency ranges, means for providing mutual coupling between said inductances used in non-adjacent frequency ranges, and means for tuning any one of said inductances through a range of frequencies. 65 70
